UNITED STATES PATENT OFFICE.

CHARLES BUSHOR, OF PHILADELPHIA, PENNSYLVANIA.

MACHINE FOR LOADING COAL, &c.

Specification forming part of Letters Patent No. 32,680, dated July 2, 1861.

To all whom it may concern:

Be it known that I, CHARLES BUSHOR, of Philadelphia, in the county of Philadelphia and State of Pennsylvania, have invented a new and Improved Machine for Loading or Unloading and Conveying Coal; and I hereby declare that the following is a full and exact description of the same, reference being had to the accompanying drawings, and to the letters of reference marked thereon.

Figure I represents an elevation, Fig. II a plan, and Figs. III and IV, end views, of my improved machine.

Similar letters represent similar parts.

The nature of my invention consists in the combination of an elevator with a horizontal and circular conveyer in such a manner that thereby the coal can be taken from one point and delivered at any other point within the reach of the machine.

In the accompanying drawings, A represents the frame of the machine, carrying a shaft *a* on its upper end, through which the whole machine is set in motion. This shaft passes through the opening of the frame-work of an elevator B, arranged with suitable rollers *n m*, over which an endless chain provided with buckets C is made to work, or the buckets may be jointed together, so as to form a chain. This elevator receives its motion through the wheel 2, fast on the end of the shaft *a*, working into the wheel 3 on the shaft *d*, on the upper end of which another wheel 4 is fastened, working into the wheel 5, fast on the shaft of the upper roller *m*. This wheel 5 works on a key on the shaft of the roller *m*, so as to be thrown in or out of gearing, as may be desired.

Above the shaft *a* is a shaft *f*, likewise supported by the frame A. This shaft *f* is provided with a long sliding piece working in suitable guides on the inside of the elevator-frame B, and has on each side a pinion 6, fast on the shaft *f*, working in suitable racks *g*, fast to the framing B.

On the end of the shaft *f* a wheel 8 is fixed, working into a pinion 9, attached to the shaft *a*. The wheel 8 is made to move sidewise on the shaft *f*, so as to be able to throw the same in or out of gear, as may be required. By means of this gearing working into the racks *g* the elevator can be raised or lowered, as may be desired.

Near the lower end of the elevator rods *h* are attached, provided with teeth 10 on the ends, at the under side, meshing into pinions 12, fast to a shaft *k*, attached to the frame A, by which this lower end of the elevator can be inclined inward or outward, turning around the shaft *f* as a center.

D is a horizontal conveyer attached at one end to the frame A, while its other end is centered in the frame G. This conveyer is provided with square drums *v w*—one at each end—over which the buckets E, jointed to each other, pass. The drum *v* is connected by means of chain-wheels and chains, or by means of suitable gearing, with the shaft *a*, and obtains in this manner motion, which is communicated to the buckets E, as well as to the drum *w* at the other end, on account of the squares on the drums being of the same size as the buckets, which, as above mentioned, being jointed together, form a chain. The motion of the drum *w* is communicated through the wheels 13 and 14 to a small shaft *i*, attached to the side of the frame of this conveyer, on the bottom of which said shaft a pinion 15 is attached.

On the center of the upright frame G a wheel *p* is arranged, turning loosely upon the same.

A conveyer H is attached to the upper part of the upright frame G, resting with its other end upon a circular railway L. The buckets N of this conveyer are moved through the pinion 16, gearing into the wheel *p*. This pinion is fast to a small shaft *y*, attached to the movable part of the frame G. On the end of this shaft *y* a wheel 17 is attached, gearing into a wheel 18, fast to the drum *x* of the conveyer H. The buckets N of this conveyer H are made with hinged bottoms capable of opening. A plate is arranged under the buckets, upon which the same rest, and which keeps the bottoms of the buckets closed. This plate is so arranged that the same can either be let down or moved away at any place within the whole length of this conveyer, by which arrangement the bottoms of the buckets, when arriving at that place, will fall open and allow the coal contained in the same to fall out. Below this plate or support for the bottoms of the buckets a board *s* is arranged on the inside of the framing of the conveyer H, capable of being turned toward either side

of said conveyer, so as to discharge the coal falling out of the buckets either on the one or on the other side, as may be desired. When the plate or support for the bottoms of the buckets N is arranged so as to support said bottoms the whole length of the conveyer, the coal will be discharged at the end of the conveyer.

When a vessel is to be unloaded, the elevator B is brought into the hold of the vessel and the coal raisep up by the same, which is then discharged through the hopper C upon the conveyer D, from which the coal is brought upon the conveyer H, and can be discharged, as above described, at any desired point within the range of this conveyer H.

The frame A, which supports the elevator and one end of the conveyer D, may likewise be arranged so as to be capable of moving upon a circular railway having the frame G as

a center, by which arrangement this elevator and conveyer can be moved in a circle around the yard and the coal taken up at any place in the yard by the elevator B and discharged at any other point by the conveyer H.

What I claim as my invention, and desire to secure by Letters Patent, is—

1. The arrangement of an elevator B and conveyer D with a circularly-moving conveyer H, substantially in the manner and for the purpose described.

2. The arrangement of the conveyer H, capable of turning at one end around a center and supporting the other end upon a circular railway, in the manner and for the purpose described.

CHARLES BUSHOR.
